HOBBY HORSE SHELL

Robert H. Wendt, Evanston, Ill.

Application April 12, 1957, Serial No. 45,723

Term of patent 14 years

(Cl. D34—15)

Fig. 1.

Fig. 2.

Fig. 3.

Fig. 4.

Fig. 1 is a perspective view of a hobby horse shell, showing my new design, the opposite side having substantially the same appearance;

Fig. 2 is a front elevational view;

Fig. 3 is a rear elevational view; and

Fig. 4 is a top plan view.

I claim:

The ornamental design for a hobby horse shell, as shown and described.
